GEORGE LISPENARD, OF NEW YORK, N. Y., ASSIGNOR, BY MESNE ASSIGNMENTS, TO THE NORDLINGER-CHARLTON FIREWORKS COMPANY, OF SAME PLACE.

CHOKING-MACHINE FOR FIRE-CRACKER BODIES, &c.

SPECIFICATION forming part of Letters Patent No. 634,176, dated October 3, 1899.

Application filed May 27, 1898. Serial No. 681,914. (No model.)

To all whom it may concern:

Be it known that I, GEORGE LISPENARD, a citizen of the United States, residing at New York, (Brooklyn,) in the county of Kings and State of New York, have invented a certain new and useful Choking-Machine for Fire-Cracker Bodies or the Like, of which the following is a specification.

My invention relates to machines for making a choke or plug to close the end of a fire-cracker or other like body.

In an application filed by me on the 27th day of May, 1898, Serial No. 681,915, I have described a choke for a fire-cracker in which the body is made of a series of convolutions of pulpy paper, such as "Chinese" paper or the like, and the present application relates to a machine which may be employed in producing the choke described in said applica-
tion.

In forming a choke for a fire-cracker by machine, where the pressure is constant, considerable difficulty has been encountered where the body of the cracker has been made of soft paper in causing the body of the cracker to withstand the pressure necessary to efficiently form the choke. When the body of the paper is made up of a number of convolutions of comparatively thin and hard paper, it presents sufficient resistance, both longitudinally and transversely, to offset the necessary pressure used in forming the choke, but when a fire-cracker body is employed in which the convolutions are made of thick and pulpy paper, there being necessarily but few of them, the body presents comparatively little resistance transversely or longitudinally to the action of the choking means.

My present invention therefore relates to a machine by means of which an efficient choke can be made in a fire-cracker body composed of a few convolutions of comparatively thick and pulpy paper, such as is known in the trade as "Chinese" paper.

My invention therefore primarily consists in a suitable bed-plate, a series of pins grouped closely together and having their upper ends formed on an angle converging to a point central to the group, the pins act-

ing to detach one or more of the interior convolutions of the body from the exterior convolutions and compress the detached or disturbed portions of the convolutions, combined with means for supporting the fire-cracker body while the pins are acting, as above re-
cited, so as to prevent longitudinal transverse distortion of said bodies.

In an application filed by one Charles L. Curtis on the 7th day of February, 1898, Serial No. 669,370, a machine is described for forming the choke in a fire-cracker body. This machine was designed to operate on fire-cracker bodies formed of a number of convolutions of comparatively hard and thin paper in which comparatively a great number of convolutions were employed, the large number of convolutions and the stiffness of the paper offering lateral and longitudinal resistance to the operation of the machine while forming the choke. In that machine also pins were employed, but the wedge action of the pins was not as great as is contemplated in my present invention, and they were merely used for the purpose of separating some of the interior convolutions from the exterior convolutions, the final act of forming the plug or choke being due to the operation of a plunger which bodily moved all the separated convolutions inwardly and compressed them to a marked degree into concentric rings which formed abutments within the bore of the body. By reason of the toughness of the paper operated upon it was necessary to employ during the plugging operation a central pin or rod, about which the choke was formed in order to leave a sufficient opening, into which was subsequently passed the discharging-stem. In my present invention I entirely eliminate the subsequent operation of the plunger to form the choke and form it by the action of the pins, at the same time forming the choke immediately about the stem, thus avoiding the necessity of the subsequent operation of inserting the stem after the choke is formed.

My invention also contemplates means whereby the chokes at both ends of the body can be formed either simultaneously while

the stem is in place or at different periods, both, however, without removing the body from the support in which it is placed.

My invention further contemplates a machine in which gangs of these separate choke-forming devices are employed in which the elements thereof coöperate to form an efficient time and labor saving machine.

My invention therefore consists substantially in the construction and combination of parts hereinafter described, and further pointed out in the claims.

In the drawings forming part of this specification, Figure 1 is a side elevation of the machine embodying my invention; Fig. 2, an end elevation thereof; Fig. 3, an under side plan view of the movable carrier-frame, partly in section, on the line $x-x$, Fig. 1, looking in the direction of the arrow; and Fig. 4 is a plan view of the base of the machine, partly in section, on the line $y-y$, Fig. 2, looking in the direction of the arrow.

Similar numerals of reference indicate corresponding parts throughout the several views.

I believe that the several features of my invention are entirely new with me, and therefore I do not intend to limit myself to the specific construction of the machine herein shown and described, but prefer the same for many reasons.

The embodiment of my invention, as illustrated in the accompanying drawings, consists, substantially, as follows: At 1 is a suitable bed-plate supported in the desired manner. On this bed-plate are secured upwardly-extending choking-pins 2, preferably three in number, set equidistant apart, each pin having at its upper inner portion an inclined face 3, the incline of which converges toward the mutual central axis of the grouped pins, the incline forming entrant and compressing points. About these pins at a distance apart corresponding with the diameter of the fire-cracker body to be operated upon are secured restraining or steadyng pins 4 5, preferably four in number, for a purpose herein-after described.

The means thus far is amply sufficient to produce the choke described in my application before set forth, which is formed as follows: At 6 is a fire-cracker body comprising a series of convolutions 7 of paper forming a bore 8. The body of the cracker is placed within the restraining-pins 4 5, the wedge-shaped points of the choking-pins being located at a sufficient distance apart to take in the desired number of interior convolutions of the body. At 9 is the stem, the end of which may project out from between the choking-pins, as shown in Fig. 1. A sharp blow on the top of the body will drive it down onto the pins, forcing a number of the interior convolutions 10 of the body away from each other at the places where the pins enter, the incline or wedge of the pins acting to compress or force the displaced por-

tions of the interior convolutions inwardly toward the stem and to compress the adjacent undisturbed portion of the interior convolutions upon each other, as described in my before-mentioned application, which efficiently chokes the end of the bore as against interior forces during explosion and to properly hold the stem in place, as at 11.

Thus far described it will be noticed that my invention does not require the coöperation of other mechanical elements to properly form the choke, as the device, consisting simply of the bed-plate, the upwardly-extending choking-pins, and the steadyng-pins, (which might be in the form of a tube,) are all that are essential for the production of the particular form of choke described in my above-mentioned application, the steadyng-pins being preferred, because they allow the body to be seen during the choking operation; but it will be apparent that both time and money can be saved by operating upon a number of fire-cracker bodies at once and to complete the operation of plugging both ends of the body at one time or both ends without removing the body from the steadyng-pins. To produce these results I have embodied this portion of my invention as will now be described.

The bed-plate 1 is provided with a duplication of the choking-pins 2 and the steadyng-pins 4 5, each set of the latter, preferably four, steadyng-pins having a separate set of choking-pins disposed between them, and in order to save space on the bed-plate and to cause the two inside pins 5 to support two adjacent fire-cracker bodies I arrange the pins in the direction of their lengths so as to oppose each other, as shown in Fig. 4, the second fire-cracker body from either end of the range of pins resting against the two inside centering-pins 5. By this arrangement I dispense with a separate and complete set of pins for each body and cause each set of steadyng-pins to support the next fire-cracker body, thus saving space on the bed-plate and expense and reducing the number of parts.

Thus far it will also be noticed that the operation of forming a choke at one end can be performed by giving a blow to the end of the bodies after they have been placed in position, as indicated in Fig. 1; but in order to form the choke at both ends of the body without removing the body from the steadyng-pins I provide the following construction: At 12 are two guide-rods secured in the bed-plate 1 and extending upwardly from the end of the range of steadyng-pins. At 13 is a frame 125 adapted to be moved up and down on said rods, for which purpose handles 14 are provided, which extend outwardly from the cross-piece 15 of the frame, and in order to cause said frame to move freely up and down on the rods I form a guideway comprising three rollers, two interior 16 17 set one above the other and mounted on a shaft in arms 18, extending from the cross-piece, the groove of

the rollers bearing against the curved side of the rods 12, the cross-piece 15 being bifurcated, as at 19, Fig. 3, to allow the rods 12 to pass freely up and down, the ends 20 of the 5 projections 19 being provided with a shaft on which a single outer grooved roller 21 is mounted, which roller bears against the other side of the rod. This forms an efficient guide for the cross-bar 15 of the frame, steadyng 10 it, keeping it in perfect alinement, and maintaining its parallelism with the bed-plate, which latter is essential to forming the chokes in the bodies between the lower range of steadyng-pins at equal and uniform distances 15 from the end of the body and to compress the convolutions forming the choke in each of the separate bodies to a uniform degree.

By reference to Fig. 3 it will be noticed that the cross-bar 15 is provided with a series 20 22 of depending choking-pins, each series comprising three pins 23, arranged and constructed in the same manner as the lower choking-pins 2, and that from each side of the series 22 of choking-pins depend a further 25 series of centering-pins 24, located on a line passing through the mutual center of each group 22 of choking-pins, the upper and lower series of choking-pins 2 23 being in vertical alinement relatively to each other, while the 30 upper and lower centering and steadyng pins are staggered one in relation to the other, the upper centering-pins being wider apart for a purpose hereinafter described.

As before stated, it is intended to operate 35 the upper movable frame 13, carrying the upper range of centering and choking pins, by the hand—that is, to cause its range of choking-pins to engage the upper end of the bodies while they are held by the steadyng-pins of 40 the lower range—and in order to raise the frame out of contact with the bodies and sufficiently remove it therefrom to allow of the bodies being expeditiously removed from the range of steadyng-pins without hindrance 45 from the pins of the upper frame I have provided a counterweight 25, shown as being secured to a cord 26, passing over pulleys 27 28, suitably supported, the other end of the cord being secured to an eyebolt 29, passing 50 through the cross-bar of the frame. However, instead of using the counterweight its equivalent, a spring, may be employed, the frame being moved downwardly to form the choke against the stress of the spring, which 55 when pressure is released from the frame will raise the frame from the pins in its upward position. At any desired height on the rod stops may be formed, as by a collar 30, in order to arrest the ascent of the frame at any 60 desired height.

The operation is as follows: The bodies being placed in position between the lower steadyng-pins, as before described, with the stem in place, as indicated in Fig. 1, the desired 65 number of interior convolutions of the body being embraced by the lower range of choking-pins, the frame is moved sharply downward,

causing the upper range of centering-pins to embrace the sides of the body between the lower steadyng-pins, perfectly centering the 70 frame over the interior convolutions which it is intended the upper choking-pins shall embrace, and acting further to steady and brace the body during the impact received from the frame, the impact being further continued 75 driving the upper range of choking-pins into the bodies, moving the lower end of the bodies down onto the lower range of choking-pins, forcing the lower range of choking-pins into the lower end of the body, the continuation 80 of the movement of the frame forming both the upper and lower chokes about the stem, the downward movement of the bodies on the lower range of choking-pins being finally, if pressure is continued to that point, arrested 85 by the bed-plate, and the downward movement of the frame being arrested by the cross-piece 15 coming in contact with the top of the bodies; and should the pressure of the impact given to the bodies by the movable 90 frame be so great as to tend to distort the body the lower steadyng-pins will come in contact with the under side of the cross-bar of the frame and arrest its movement, the height of the lower steadyng-pins being preferably so proportioned that they will be longer or higher from the bed-plate than the fire-cracker body would be when its lower end 95 rested on the bed-plate, thus checking the downward movement of the frame and preventing undue pressure being placed upon the fire-cracker body.

It will be apparent from the foregoing that my invention can be embodied in devices other than the one illustrated without departing 105 from the spirit of my invention.

Having described my invention, I claim—

1. A device of the kind described, the combination with a stationary bed-plate or support, of a group of upwardly-extending pins, 110 said pins having produced upon their upper portions inclined or wedge-shaped faces converging toward the central axis of the group, and upwardly-extending steadyng-pins secured to said bed-plate and grouped about 115 the first-mentioned pins, said steadyng-pins extending above the choking-pins, substantially as described.

2. In a device of the class described, the combination with a stationary bed-plate, of a 120 series of groups of choking-pins, each group comprising a plurality of pins having inclined faces formed at their tops, the faces converging toward the mutual center of each of the group of said pins, steadyng-pins affixed to 125 said base and grouped about the choking-pins, a frame movable to or from said base, means for supporting said frame in said movement and maintaining its parallelism with said base, said frame carrying counterpart depending choking-pins and staggered centering-pins, substantially as described.

3. In a device of the kind described, the combination with a stationary bed-plate or

support, of a group of upwardly-extending choking-pins, said pins having produced upon their upper portions inclined or wedge-shaped faces converging toward the central axis of the group, steadyng-pins secured to the bed-plate about the choking-pins, and extending above them, and means for impaling a cracker-body on said choking-pins, substantially as described.

10. 4. In a device of the class described, the combination with the bed-plate, the grouped choking-pins extending upwardly therefrom, the steadyng-pins 4, 5, grouped about the choking-pins at the angles of a square, a movable frame, a group of choking-pins depending therefrom, centering-pins set transverse of the frame and in line with a point intermediate of two of the steadyng-pins, and means for operating and guiding said frame to and from the bed-plate; substantially as described.

5. In a device of the class described, the combination with a stationary bed-plate, of a group of choking-pins, said pins having inclined faces formed at their tops, the faces converging toward the mutual center of the group, steadyng-pins affixed to said base and grouped about the choking-pins, a further group of choking-pins movably suspended above the first-mentioned choking-pins, and means for supporting said second group of choking-pins in its movement to or from the first-mentioned group, substantially as described.

30. 6. In a device of the class described, the combination with a stationary bed-plate, of a group of choking-pins, said pins having inclined faces formed at their tops, the faces

converging toward the mutual center of the group, steadyng-pins affixed to said base and grouped about the choking-pins, a frame supported to move to and from the said base, a further group of like choking-pins depending from said frame in line with the first-mentioned group, and means to limit the extreme 45 upward and downward movement of said frame, substantially as described.

7. In a device of the class described, the combination with a stationary bed-plate, of a group of choking-pins, said pins having inclined faces formed at their tops, the faces converging toward the mutual center of the group, steadyng-pins affixed to said base and grouped about the choking-pins, a frame supported to move to and from the said base, a 50 counterpoise for raising the frame, and means to limit the extreme upward and downward movement of the frame, substantially as described.

8. In a device of the class described, the combination with the base 1, of the upright 12, the cross-bar 15 having superposed rollers 16, 17, and an outer roller 21 at each end, each set of the rollers engaging the uprights 12, alining groups of choking-pins extending 65 upwardly from the base and downwardly from the cross-bar, and steadyng-pins on the base and centering-pins on the cross-bar, substantially as described.

Signed at the city, county, and State of 70 New York this 26th day of May, 1898.

GEORGE LISPENARD.
